(57) **CLAIM**

The ornamental design for a flash drive, as shown and described.

DESCRIPTION

FIG. 1 is a perspective view of a flash drive showing our new design;

FIG. 2 is a front elevational view thereof;

FIG. 3 is a rear elevational view thereof;

FIG. 4 is a left side, elevational view thereof;

FIG. 5 is a right side, elevational view thereof;

FIG. 6 is a top plan view thereof;

FIG. 7 is a bottom plan view thereof; and,

FIG. 8 is a perspective view of FIG. 1 with a plug rotated.

1 Claim, 8 Drawing Sheets

FIG. 1

FIG. 2

FIG. 3

FIG. 4

FIG. 5

FIG. 6

FIG. 7

FIG. 8
